UNITED STATES PATENT OFFICE.

JOEL J. DYE AND WILLIAM A. LUCAS, OF NEWARK, NEW JERSEY, ASSIGNEES TO
BUTTERWORTH-JUDSON CORPORATION, A CORPORATION OF NEW YORK.

OUTLET FOR ACID-RECEPTACLES.

1,249,728.

Specification of Letters Patent. Patented Dec. 11, 1917.

Application filed June 12, 1917. Serial No. 174,188.

To all whom it may concern:

Be it known that we, JOEL J. DYE and WILLIAM A. LUCAS, citizens of the United States, residing in Newark, New Jersey, 5 have invented certain new and useful Improvements in Outlets for Acid-Receptacles, of which the following is a specification.

The invention aims to provide an improved outlet for acid concentrators or 10 other receptacles and especially for receptacles made of brickwork or the like. Most acid concentrators have outlets consisting of ordinary pipes with flanges which are bolted to the wall of the concentrator, with 15 interposed gaskets or packing material. This method, and in fact all methods in which hot acid runs directly over the gaskets of the joints, are very unsatisfactory. The gaskets are soon deteriorated by the 20 hot acid and the joints leak, with a consequent expense and loss of time in repairs. The principal purpose of our invention is to make a joint which will not suffer such deterioration and which has certain other 25 advantages referred to in detail hereinafter.

The accompanying drawings illustrate an embodiment of the invention.

Figures 1 and 2 are diagrammatic sections, horizontal and vertical respectively, 30 of an acid concentrator;

Fig. 3 is an enlarged vertical section (on the line 3—3 of Fig. 4) showing one of the outlets;

Fig. 4 is a plan of the two outlets;

Fig. 5 is a section on the line 5—5 of Fig. 4.

Referring to the embodiment of the invention illustrated, the concentrator has side walls A, end walls B and a roof C made of 40 refractory material (Fig. 2). Two practically identical outlets are illustrated, so that either may be used while the other is being cleaned or repaired. One outlet takes the acid through the lower end of a 45 side wall A and the other through suitable openings in the end wall B. Except for the difference in direction of the passages leading to the gates hereinafter described the two outlets are identical. The tank is constructed as shown in Fig. 3 of a lead trough 50 D on which is an insulating or packing layer E and a course, or several courses of brick-work F finished off with a flooring of tiles G. This floor structure is extended continuously under the passage H through the

wall of the concentrator and is extended beyond the latter to carry the gateway by which the flow of acid to the outlet pipe can be stopped. The projecting portion of the floor is supported on a steel support or 60 bracket comprising a floor portion J resting on the foundation K of the concentrator and provided with a flange L bearing against the face of said foundation, and comprising a front wall M and side walls 65 N, the latter being also flanged and fastened to the usual steel bracing of channel beams N' or to any other convenient part of the concentrator. This steel support carries not only the projecting floor but the entire outlet box. The latter consists of a block O of brickwork or other refractory material with the passageway through it communicating with the passage H through the wall of the concentrator, the bottom of this passage being closed by the extended floor structure of the concentrator and the top of this passage being open except for a removable cover P (Fig. 3) of tile or the like. 70 At its outlet end the aforesaid passage 75 communicates with the outlet box hereinafter referred to. The block of brickwork forming the outlet box is surrounded on its front face and on its side faces by the lead and packing sheets D and E which are bent up 80 from the underside, extend clear to the top, the lead sheet D being flanged over the upper edge of the brickwork as shown in Figs. 85 3 and 4. The brickwork lining or box O is formed with two pairs of vertical grooves Q and R. These grooves are adapted to accommodate gates S and T made of tile and extending upward through suitable openings in the cover P. The intermediate portion of the passage through the box constitutes a space U between the two gates which can be packed with sand or other packing 90 material to make a tight closure if this should be necessary, though ordinarily a luting in the grooves Q and R around the 95 edges of the gates will be sufficient to prevent seepage of acid.

The cover P serves to prevent the escape of gas. The holes in the cover through which the gates S and T pass, should be sealed with sand or other packing material. And when the gates are withdrawn to permit the passage of acid, a solid cover may be substituted in place of P; a luting of any sort may be placed under the margin of the 100 105 110

cover to prevent the escape of gas under the same.

The outlet pipe V is made of acid-proof iron with a flange W located some distance beyond the inlet end of the pipe, the inlet end X extending through an opening in the front wall O of the brick outlet box or boot and the flange W being bolted to a flange Y on the end of a tubular extension Z of the lead casing D. A tubular packing 2 is located between the pipe on the one hand and the brickwork on the lead casing on the other and has a flange between the flanges W and Y. An iron ring 3 is located back of the lead flange Y to take the pressure of the heads of the several bolts 4. The several flanges referred to are notched as shown in Fig. 5 so that the bolts can be loosened and rapidly withdrawn in a radial direction when the joint is to be broken. By this method of attachment of the pipe the acid will not come in direct running contact with the gasket between the flanges and will not wear and leak as in previous constructions. If there is any seepage of acid into the packing at the inner end of the latter it will be so slight as to be harmless.

The pipe is bent as shown and at the junction of the horizontal and vertical parts is provided with a hand hole 5 surrounded by a bell flange and normally closed by a plate 6 with paste or luting around the edges. On removing the plate a rod or other instrument can be passed through the horizontal and vertical portions of the pipe to clean the same.

In Fig. 1 one of the outlet boots or boxes is indicated at O and the other at O'. The latter is arranged with the passage through it at right angles to the passage H through which the acid passes from the concentrator to the box; and there are two of these passages H leading to this box. The two pipes V from the respective boxes O and O' discharge into a common chute or vessel 7 which is preferably of brick with a lead casing like the boxes O and O' and which discharges through a pipe 8 (Fig. 2) into a cooler 9.

The acid in the concentrator stands normally at about the level indicated in Fig. 3. Consequently there is a seal of the liquid acid between the flame or hot air within the concentrator and the pipe and joints outside, and there is much less expansion of the parts of the joints by heat than where the pipe extends into the concentrator. The temperature of the air within the concentrator may, for example, be about 2,000 or 2,500 degrees Fahrenheit while the temperature of the acid is only about 700 degrees.

The term "refractory material" is used herein to define the tiles, bricks and the like as distinguished from the metal parts of the structure.

Though we have described with great particularity of detail certain embodiments of our invention yet it is not to be understood therefrom that the invention is restricted to the particular construction illustrated. Various modifications of the same in the details and in the arrangement of the parts may be made by those skilled in the art without departure from the invention as defined in the following claims.

What we claim is—

1. An acid receptacle of refractory material provided with a box of similar material on the outside communicating with said receptacle, in combination with an outlet pipe communicating with said box, and means for closing the passage through said box. 80

2. An acid receptacle of refractory material provided with a box of similar material on the outside communicating with said receptacle, in combination with an outlet pipe communicating with said box, and means for closing the passage through said box, comprising a pair of gates with a space between them adapted to be filled with packing material. 85

3. An acid receptacle of refractory material provided with a box of similar material on the outside communicating with said receptacle, in combination with an outlet pipe 95 communicating with said box, and a removable cover for said box.

4. An acid receptacle of refractory material provided with a box of similar material on the outside communicating with said receptacle, in combination with an outlet pipe communicating with said box, and a sheet of acid-proof material extending under the floor of said receptacle and surrounding the refractory material of said box. 100

5. An acid receptacle of refractory material provided with a box of similar material on the outside communicating with said receptacle, in combination with an outlet pipe communicating with said box, and a sheet of acid-proof metal surrounding said box and having a tubular portion extending outward therefrom, said outlet pipe extending to the interior of said box and having at a point outside of the same a flange which is 110 clamped to the end of said tubular portion of acid-proof metal. 115

6. An acid receptacle of refractory material provided with a box of similar material on the outside communicating with said receptacle, in combination with an outlet pipe communicating with said box, and a sheet of acid-proof metal surrounding said box and having a tubular portion extending outward therefrom, said outlet pipe extending to the 120 interior of said box and having at a point outside of the same a flange which is clamped to the end of said tubular portion of acid-proof metal, said pipe extending from said box in a horizontal direction and 125 130

then downward, and having a hand hole at the bend permitting access to both the horizontal and vertical portions of the pipe.

7. An acid receptacle of refractory material provided with a box of similar material on the outside communicating with said receptacle, in combination with an outlet pipe

communicating with said box, and a bracket of metal attached to said receptacle and supporting said box.

In witness whereof, we have hereunto signed our names.

JOEL J. DYE.

WILLIAM A. LUCAS.
